[57] CLAIM

The ornamental design for a golf club head, as shown and described.

DESCRIPTION

FIG. 1 is a top plan view of a golf club head showing my new design;

FIG. 2 is a left side elevation view of the golf club head; FIG. 3 is a right side elevation view of the golf club head;

FIG. 4 is a front elevation view of the golf club head; FIG. 5 is a rear elevation view of the golf club head; and,

FIG. 6 is a bottom view of the golf club head.

The broken line showing of a fragmented shaft is for illustrative purposes only and forms no part of the claimed design.

Fig. 1.

Fig. 2.
